UNITED STATES PATENT OFFICE.

RICHARD H. TAYLOR, OF NEW YORK, N. Y., ASSIGNOR TO SOCIETE DU CARBURATEUR ZENITH, OF LYONS, FRANCE, A CORPORATION OF FRANCE.

CARBURETOR.

Application filed November 29, 1919. Serial No. 341,519.

To all whom it may concern:

Be it known that I, RICHARD H. TAYLOR, a citizen of the United States, residing at New York city, in the county and State of New York, have invented a new and useful Improvement in Carburetors, of which the following is a full, clear, and exact description.

The present invention relates to the art of carburetion as applicable particularly to internal combustion engines.

The principal object of the present invention is to provide a carburetor with means capable of supplying a rich mixture upon starting the engine, which means is absolutely inoperative during the time the engine is operating on its own power and while operating on a mixture fed from an idling by-pass.

A further object of the present invention is to provide a carburetor having means of the type described, which means is automatically operable each time the engine has been brought to a standstill, and is then started.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a longitudinal section through one form of carburetor having my improved device applied thereto, and

Figure 2 is a section on the line II—II of Figure 1.

The present invention is applicable to all carburetors of that class in which a measuring orifice placed below the normal level of the fuel, feeds the fuel into a well open at some point to the atmosphere, and having a passage or passages conducting the fuel into the carbureting chamber; where the effect of the passage or passages is to bring about a gradual lowering of the fuel in the well.

I am aware that heretofore carburetors have been constructed which have been provided with means for supplying a rich mixture upon starting the engine either by the use of a supplemental well, a pump device,

or a combination of the two. Such means have, however, been so controlled and operated that they are operative throughout the entire running period of the engine, or at least during the idling or slow-speed running periods thereof. My invention differs fundamentally from devices of this character, in that it ceases to function immediately after the engine has started running on its own power and is operating on a mixture fed from an idling by-pass, and remains inoperative until after the engine has been brought to a standstill and again started. This operation has by experiment been found to be very successful, in that the running mixture once properly regulated is not rendered less effective by the feeding of an increased amount of fuel into the carbureting chamber.

Referring more particularly to the drawings in which I have illustrated my improved device applied to a carburetor of the type shown in Baverey Patent No. 1,186,371, there is provided the usual constant level chamber 2, having a float 3 therein operating, as well understood, to regulate the flow into the chamber through the inlet 4. A suction controlled nozzle 5, serving to supply at least a portion of the fuel for running conditions and receiving its supply of fuel through a channel 6, is located to discharge into the carbureting chamber 7 below the throttle 8. This nozzle forms no part of the present invention, and does not cooperate with the elements of the invention.

A main well 9 is formed in the casing, adapted to be fed through the calibrated orifice 10, and in turn feeding, through the channel 9', the compensating nozzle 11 surrounding or adjacent to the main nozzle 5. A chamber 12 preferably communicates with the well 9 and is open to the atmosphere through a suitable opening 14 above the liquid level therein. Mounted within the chamber 12 is a low-speed feed device comprising a fuel nozzle 15 communicating with a passage 16 entering the carbureting chamber adjacent the throttle valve 8 for feeding fuel to said chamber when the throttle is nearly closed.

Adjoining the atmospheric well 9 is a secondary well 17 of any desired size. This secondary well is in turn provided with an opening 18 to the atmosphere, and receives its supply of fuel through the opening or

channel 19 formed in the wall of the main well. This opening is so positioned that fuel passes from the main well into the secondary well when the engine is at a standstill, but is so positioned with relation to the fuel level that as soon as the engine starts running on its own power and while it is operating on a mixture fed from the low speed device referred to, the fuel level in the main well will 5 drop below the opening and therefore will 10 not supply the secondary well with fuel. A tube 20 extends into the secondary well and opens at its upper end into the carbureting chamber preferably above the throttle valve. 15 With the construction described, the operation will be as follows:

When the motor is cranked, the throttle valve being kept in a nearly closed position, the high vacuum obtained above the throttle 20 will draw gasoline through the passage 16 and, in addition, will draw through the tube 20 the gasoline which has accumulated in the secondary well 17. As soon as the motor is operating if the throttle is kept in the 25 position described, the fuel level in the well 9 will be lowered, as the slow speed feed terminating adjacent the throttle keeps supplying fuel to the motor. This lowering of the fuel is a necessary consequence, due to the 30 fact that the main well is fed through the calibrated orifice 10. All of the fuel entering the carbureting chamber through the passage 16 must be supplied through the calibrated orifice, and as the well 9 is open to 35 the atmosphere through the hole 14, the air drawn therethrough helps to satisfy the suction so that the flow through the measuring orifice is not a true suction flow. In reality 40 this flow is intermediate a true suction flow and a gravity flow. From the foregoing, it will be apparent, therefore, that in order to produce a flow of fuel through the calibrated orifice there must be a lowering of the fuel 45 level in the main well. The effect of this lowering is to uncover the communication 19 between the main well and the secondary well and thereby prevent any more fuel finding its way into the secondary well as long 50 as the engine is running. As soon, however, as the engine is brought to a standstill, the fuel level in the main well will be raised and the secondary well will again be filled in the

manner described. In order to accomplish the results desired, the opening for feeding the secondary well must be located below the 55 fuel level in the main well when the engine is at a standstill, and above the fuel level therein when the engine is running.

The advantages of the present invention arise from a construction in which only a 60 predetermined accumulated charge is fed during the starting of the motor, and this feed is automatically rendered inoperative as soon as the motor is running under its own power, and under such conditions that 65 the idling by-pass or slow speed device is delivering fuel to the motor.

I claim:

1. In a carburetor, a carbureting passage, a throttle therefor, a secondary priming fuel 70 feed for said passage communicating therewith and effective with the throttle in substantially closed position, a slow speed feed communicating with said passage and effective upon initial opening of the throttle, and 75 a fuel supply for said secondary feed adapted to be drawn upon by said slow speed feed when the throttle is opened to cut off the fuel supply to the secondary feed when the engine supplied by the carburetor begins operating on its own power and while it is operating on the mixture from the slow speed feed, substantially as described.

2. A carburetor having a constant level chamber, a carbureting passage, a throttle 85 valve in said passage, an atmospheric well, means for feeding fuel from the atmospheric well to the carbureting passage, means for feeding fuel from the constant level chamber to the atmospheric well, a second well in 90 communication with the upper portion of the atmospheric well, and an auxiliary fuel feed for temporarily feeding additional fuel to the carbureting passage above the throttle from the second well, the feed of fuel from said second well being adapted to be cut off when the engine supplied by the carburetor begins operating on its own power and while it is operating on a mixture from the atmospheric well, substantially as described.

In testimony whereof, I have hereunto set my hand.

RICHARD H. TAYLOR.
